DESIGN FOR A GRUBBING HOE

Blaine Farmer, Repton, Ky.

Application May 4, 1949, Serial No. 92,158

Term of patent 14 years

To all whom it may concern:

Be it known that I, Blaine Farmer, a citizen of the United States, residing at Repton, in the county of Crittenden and State of Kentucky, have invented a new, original, and ornamental Design for Grubbing Hoes, of which the following is a specification, reference being had to the accompanying drawing, forming part thereof.

Figure 1 is a front perspective view of a grubbing hoe, showing my new design.

Figure 2 is a rear perspective view thereof.

Figure 3 is a transverse sectional view of the same taken on the line 3—3 of Figure 1, looking in the direction of the arrows.

The characteristic features of my design reside in a grubbing hoe of the contour shown and having a pair of fins with a fillet therebetween of the arrangement and configurations shown.

I claim:

The ornamental design for a grubbing hoe, as shown and described.

BLAINE FARMER.
